Attorney:

UNITED STATES PATENT OFFICE.

JOHN G. AVERY, OF SPENCER, MASSACHUSETTS, ASSIGNOR TO THE DUTCHER TEMPLE COMPANY OF MASSACHUSETTS.

LOOM-TEMPLE.

SPECIFICATION forming part of Letters Patent No. 416,708, dated December 10, 1889.

Application filed March 12, 1889. Serial No. 302,973. (No model.)

To all whom it may concern:

Be it known that I, JOHN G. AVERY, a citizen of the United States, and a resident of Spencer, in the State of Massachusetts, have 5 invented a new and useful Improvement in Loom-Temples, of which the following is a specification.

This invention relates to "automatic" temples for power-looms and to a peculiar style 10 of such temples, in which a pair of jaws intermittently grasp and hold the cloth within a few picks of the most advanced position of the reed, or nearer the reed than has heretofore been practicable.

15 The invention consists in certain novel combinations of parts hereinafter set forth and claimed.

The objects of the invention are, first, to provide at once for firmly holding the cloth 20 in a properly-stretched condition while the lay is in motion, and for freeing it from the holding-teeth of the jaws preliminary to and during the movements of the cloth; secondly, to automatically open and close the jaws without 25 the aid of springs other than those formed by the plates or bars which carry said jaws; thirdly, to provide for readily opening the jaws by hand to free the cloth when it is to be taken out of the loom finally or out of 30 either temple temporarily, as in the case of a pick-out; fourthly, to provide for automatically closing the temples if they are accidentally left open; fifthly, to provide for the movement of the improved temples with the 35 cloth when the filling is beaten up by the reed; sixthly, to adapt the same in a peculiar way to yield automatically should the shuttle get caught between the reed and either temple, and, seventhly, to render the same adjustable for different widths between breast-beam and lay, as well as for different widths 40 of cloth.

Two sheets of drawings accompany this specification as part thereof.

45 Figure 1 of the drawings, Sheet 1, represents a top view of one of my improved temples with its holder for the left-hand side of a power-loom. Fig. 2 represents an elevation of the same. Fig. 3 represents a half-face 50 view of the holder with its spring in place. Fig. 4 represents a vertical section through

the holder and its spring on the line 44, Fig. 3. Fig. 5 represents a fragmentary elevation showing the opposite edge as compared with Fig. 2, and representing the jaws as opened to 55 free the cloth. Fig. 6, Sheet 2, represents a fragmentary top view of the jaw end of the same temple on a larger scale. Fig. 7 represents an end view of the same with the jaws closed. Fig. 8 represents a like view with 60 the jaws opened, and Fig. 9 represents a fragmentary top view illustrating a modification.

Like letters of reference indicate corresponding parts in the several figures.

The temple proper (represented in the drawings) comprises a pair of horizontal jaws A A², one above the other, a burr-roll B, with its spindle B' immediately behind said jaws, and preferably a rigid finger C, behind the burr-roll and parallel therewith, all of which 70 are supported by a bar composed of elastic plates D D², preferably of suitable steel.

The jaws A A² are conveniently and preferably formed on or in one part with the respective plates D D² at the reed end of said 75 bar. The plates D D² are tightly united at the opposite extremity of the bar, with a spacing-piece D' between them, the plates D D² being so set as to keep the jaws normally 80 closed to the required extent to act on the cloth. The jaws hold the cloth by means of suitable teeth h, Figs. 2 and 5 to 8, which are conveniently and preferably formed by serrating upturned edges on strips of steel which are riveted upon the face of one of the jaws, 85 preferably the lower one. Between two such teeth-strips, parallel with each other and with the lay, a freeing-tongue f is arranged, as shown in the same figures. It is preferably of spring-steel, riveted fast to the opposite jaw 90 at its bar end, and provided with a supporting-pin s, which occupies a hole in the toothed jaw at its outer end.

The burr-roll B is preferably composed of independent rotary disks toothed like said 95 teeth-strips, separated to the proper extent for particular fabrics by washers, and suitably confined on the spindle B'. The spindle B' and finger C are always parallel with each other. They may be parallel with the jaws, 100 as shown in Fig. 1, or inclined, so that the burr-roll shall pull the cloth toward the selv-

age, as shown in Fig. 6. In the particular temple represented said spindle and finger are each attached to the bar-plate D by a pair of screws s' s^2 , and two sets of holes are provided for the screws s^2 , farthest from the cloth-space, so that by shifting these screws the spindle and finger may be fastened in either position, as may be desired. Owing to the difficulty of keeping screws tight on looms, 10 the spindle and finger will preferably be riveted fast in the chosen position. This may be done by upsetting the screws so that they cannot work loose. Behind said finger C a spindle E' is attached to one of the plates D 15 D², (preferably the upper plate D,) so as to be parallel with the jaws A A², and upon this spindle a cam or eccentric E is mounted, which directly or indirectly engages with the other plate D². A wear-plate w is preferably attached to the bottom of the slotted portion of the bar to coact with the eccentric. The eccentric is carried by the upper end of a lever-shaped tappet F, arranged to coact with the race of the lay. It has been provided with a 20 screw s^3 , perpendicular to its face, furnished with a jam-nut j, Figs. 2 and 5, to form by the head of the screw an adjustable contact-surface on the tappet; but this is not considered essential.

30 At that edge of the supporting-bar farthest from the cloth-space a finger-lever F² is located in line or nearly in line with the tappet F, and carries a crank or eccentric G, having suitable bearings G' between the plates D D², the bearings being attached to one plate and the crank or eccentric engaging with the other one. The finger-lever is normally retracted, as represented in Figs. 1, 2, 6, and 7. When turned into effective position, as represented 35 by Fig. 5, it is preferably within reach of the race of the lay and adapted to be returned to retracted position by its impact, the bearings G' being to this end parallel with the lay.

Immediately behind the tappet F a contact-piece c is attached to the bar-plate D², to form 40 a renewable contact-surface touched by the tappet F every time it is actuated by the lay. Behind this point the supporting-bar is extended to the required length for a given pattern of loom. Its rear end is fitted to a bar-receiving chamber perpendicular to the lay formed in the body part H of a "holder" and provided with a flattened spiral spring I, which coacts with a shoulder s⁴ on the bar to hold 45 the latter normally projected. A pin p, extending from side to side of the holder-body in front of the spacing-piece D', limits the protrusion of the bar. A set-screw s⁵, Figs. 1 and 2, acting through a wear-plate w² on 50 one edge of the bar, steadies its movements. A pair of longitudinally-slotted lugs l on the sides of the holder-body H coincide with a pair of vertically-drilled and tapped bosses b' on the face of a flange part H², provided 55 with the customary horizontal slot s⁶, and said body part and flange part are united by screws s⁷, passing through said lugs into said

bosses. The body part H of the holder is also preferably made in two pieces, as shown, so that the walls of its bar-receiving chamber 70 may be readily planed smooth and true.

In the temple represented by Figs. 1 to 8, inclusive, the eccentric E and tappet F are located at the inner edge of the supporting-bar. This arrangement is preferred for light 75 work. For heavier work the eccentric and tappet may be located within a central slot in the bar, so that its spindle E' may be supported at both ends, as shown in Fig. 9. Other like modifications will suggest themselves to 80 manufacturers.

In Figs. 2 and 5 the most advanced position of the reed is represented by a vertical dotted line a, that of the front side of the lay-beam by a like line b, the effective movement 85 of the lay by arrows a', and that of the tappet F by arrows a², and the return movement of the finger-lever F² is represented by an arrow a³ in Fig. 5. The operation of the improved temple, as illustrated by these figures 90 and by Figs. 7 and 8, is as follows:

The cloth passes between the jaws A A², over the burr-roll B, and, if maximum tension be desired, thence under the finger C, which extends the contact of the cloth with the burr-roll. Ordinarily the cloth passes over the finger. The parts being properly adjusted, the jaws A A² bite the cloth within a few picks of said line a, and the contact-surface of the tappet F projects a short distance across said line b. It may be adjusted by means of the screw s³ with the aid of its jam-nut j, or preferably by means of the screws s⁷, the slotted lugs which coact with the latter affording an adjustment of greater scope to provide for different distances between the reed and the breast-beam, to which latter said flange part H² of the holder is bolted in customary manner, and adjusted thereon by means of its slot s⁶ for different widths of cloth. When the beam 100 of the lay actuates the tappet F, the first effect is upon the eccentric E and, through the same and the bar-plates D D², upon the jaws A A² and freeing-tongue f, to open the jaws and free the cloth from the holding-teeth h. The cloth is still held against lateral contraction by the burr-roll B, the toothed disks of which turn freely as the cloth is fed through the opened jaws. Within the latter the cloth runs over the freeing-tongue f, above and out of contact with the holding-teeth h. (See Figs. 5 and 8.) By the time the cloth moves, the back of the tappet strikes the contact-piece c and drives the supporting-bar into the chamber of the holder-body H, against the pressure 115 of the spring I, far enough to insure an effective fresh hold of the jaws upon the cloth when they close an instant later. Should the shuttle become accidentally caught between the reed and the jaws A A², as in stopping 120 the loom, sufficient space is afforded within the chamber of the holder-body H, between the bar-plates D D² outside of the pin p, and between the tappet F and the face of the 130

holder, to permit the device to collapse to the required extent without injury. When the lay recedes, the spring I immediately restores the bar and the parts carried thereby to their effective positions. Should a pick-out occur, or in taking the cloth from the loom, the jaws are opened by turning the finger-lever F^2 into effective position, as illustrated by Fig. 5. If it should be accidentally left in this position, it is struck by the beam of the lay at the next pick, and thereby automatically returned to its retracted position.

Having thus described the said improvement in loom-temples, I claim as my invention and desire to patent under this specification—

1. In a loom-temple, a pair of jaws having suitable teeth on one of them and provided with a tongue movable with the opposite jaw for clearing the cloth from said teeth when the jaws are opened, in combination with a rotary burr-roll and its spindle behind said jaws, a supporting-bar and a holder therefor common to said jaws and spindle, and a device having a tappet acted on by the lay for opening said jaws, substantially as hereinbefore specified.

2. The combination, with a holder, of a supporting-bar comprising a pair of plates, one or each of which is elastic, and which carry at the reed end of the bar a pair of horizontal jaws having suitable teeth on one of them and provided with a tongue movable with the opposite jaw for clearing the cloth from said teeth when the jaws are opened, and a

device having a tappet acted on by the lay for opening said jaws, substantially as hereinbefore specified.

3. The combination, with a holder, a supporting-bar comprising a pair of plates which carry a pair of horizontal jaws at the reed end of the bar, and means for automatically opening and closing said jaws, of a finger-lever provided with an eccentric having its bearings between said plates, to open the jaws at will, substantially as hereinbefore specified.

4. The combination, with a holder, a supporting-bar comprising a pair of plates which carry a pair of horizontal jaws at the reed end of the bar, means for automatically opening and closing said jaws, having a tappet acted on by the lay, of a finger-lever depending in its effective position within reach of the lay, carrying an eccentric at its upper end and having its bearings parallel with the lay between said plates, substantially as hereinbefore specified.

5. The combination, with a jaw-supporting bar carrying a lay-actuated tappet for opening the jaws and provided with a contact-piece engaged by said tappet, of a holder having a bar-admitting chamber substantially at right angles to the lay and provided with a spring which keeps the bar normally projected, substantially as hereinbefore specified.
